HANDBAG

Gella Lindemann, New York, N. Y., assignor of
one-half to Harry N. Wessel, New York, N. Y.

Application September 30, 1937, Serial No. 166,459

2 Claims. (Cl. 150—37)

The present invention relates to handbags, and is more particularly directed toward handbags provided with externally accessible compartments, into which the user may easily obtain access without making it necessary to open the principal compartment of the handbag.

It is a common occurrence for small articles to be placed in handbags, and on account of other articles in the handbag be difficult to find or locate in a hurry. The present invention contemplates a handbag wherein it is not necessary to place the more commonly used articles in the body of the bag, hence these articles do not commingle with the contents of the bag and it is possible to obtain quick access to them.

According to the present invention one of the walls of the bag is provided with an opening behind which is placed a box-like device to form one or more compartments, and flaps are carried by the body of the bag and arranged to cover the compartments, so that when the flaps are in place the complete bag presents a trim neat appearance, and yet the contents of the compartment or compartments employed are quickly available by opening the proper flap.

The accompanying drawing shows, for purposes of illustrating the present invention, two of the many embodiments in which the invention may take form, it being understood that the drawing is illustrative of the invention rather than limiting the same.

In the drawing—

Figure 1 is a view illustrating the handbag in use;

Figure 2 is a perspective view of the handbag showing two of the compartments open and one closed;

Figures 3 and 4 are cross sectional views on the lines 3—3 and 4—4, respectively of Figure 2; and

Figure 5 is a perspective view of a modified form of construction.

In the drawing a conventional style of handbag is illustrated. It has a front side wall 10, a rear side wall 11 and end walls 12 and 13. These are secured in a suitable manner to a substantially rigid bottom wall 14 covered, if desired, with some suitable covering material 15.

The side wall 10 is provided with an elongated aperture adjacent the bottom edge of the bag, the edge of this aperture being indicated at 16. A box 20 is secured in place in the opening in the side wall of the bag. This box has a bottom 21, end walls 22, side walls 23 and 24, and transverse walls, indicated at 25 and 26. This

box may be made of wood and is covered with suitable fabric covering, indicated at 27. The center compartment may, if desired, be provided with a filler 28. The outer edges of the box walls 21, 22, 23 and 24 and the outer edges of the transverse walls or partitions, are substantially flush with the wall or face 10 of the bag.

Three flaps 29, 30 and 31 are secured adjacent the edge 16 of the side wall of the bag body, and these flaps are provided with fasteners, indicated at 32, to cooperate with fasteners 33 carried by the bottom wall of the bag. The flaps may be in closed position or in open position, as indicated. The flaps 29, 30 and 31, when closed, are substantially flush with the wall or face 10 of the bag, and give the appearance, when closed, of decorative panels formed on the wall 10 of the bag proper.

The compartment at the left under the flap 29 may be used for carrying a powder box 34, and this flap may, if desired, carry a mirror 35. The center compartment may conveniently carry a revolvable coin holding device 36. While the compartment at the right may be designed to carry a pack of cigarettes indicated at 37, and the flap 31 arranged to carry a pack of matches, indicated at 38, and a key, indicated at 39. The bag is preferably provided with a lining 40. In use the bag may be handled as indicated in Figure 1, and the user may readily flip over one of the flaps to obtain access into the articles carried in the corresponding compartment.

In the arrangement shown in Figure 5, the end wall 41 of the bag is provided with an opening to accommodate a receptacle 42, which may, if desired, carry a coin box 46. The flap 43 is provided to close the receptacle.

It is obvious that the invention may be embodied in many forms and constructions within the scope of the claims and I wish it to be understood that the particular forms shown are but two of the many forms. Various modifications and changes being possible, I do not otherwise limit myself in any way with respect thereto.

What is claimed is:

1. A lady's handbag having a bag body, an outwardly opening compartment built therein with the outer edges of the compartment substantially flush with an outer surface of the bag and one side wall at the bottom of the bag, a carrier for holding segregated groups of like coins, mounted in said compartment, and a cover hinged to the bag body above the compartment and provided with a quick detachable fastener whereby

the cover can be opened and the desired coin thereafter extracted with one hand.

2. A lady's handbag having a bag body, an outwardly opening compartment built therein with the outer edges of the compartment substantially flush with an outer surface of the bag and one side wall at the bottom of the bag, a carrier for holding segregated groups of like coins, mounted in said compartment, and a

cover hinged to the bag body above the compartment and provided with a quick detachable fastener whereby the cover can be opened and the desired coin thereafter extracted with one hand, said detachable fastener in fastened position being located on the bottom wall of the bag body whereby the same is protected against accidental unfastening in said position. 5

GELLA LINDEMANN.
